[57] CLAIM

The ornamental design for a reconfigurable toy watch, substantially as shown and described.

DESCRIPTION

FIG. 1 is a front perspective view of a reconfigurable toy watch showing my new design;
FIG. 2 is a front elevational view thereof;
FIG. 3 is a right elevational side view thereof, the side opposite being a mirror image;
FIG. 4 is a rear elevational view thereof;
FIG. 5 is a top plan view thereof;
FIG. 6 is a bottom plan view thereof;
FIG. 7 is a perspective view of the strap member with the watch assembly removed;
FIG. 8 is a front side perspective view thereof;
FIG. 9 is a front elevational view thereof;
FIG. 10 is a right elevational side view thereof, the side opposite being a mirror image;
FIG. 11 is a rear elevational view thereof;
FIG. 12 is a top plan view thereof;
FIG. 13 is a bottom plan view thereof;
FIG. 14 is a front side perspective view of the watch assembly showing portions thereof in the first alternate position;
FIG. 15 is a front elevational view thereof;
FIG. 16 is a right elevational side view thereof, the side opposite being a mirror image;
FIG. 17 is a rear elevational view thereof;
FIG. 18 is a top plan view thereof;
FIG. 19 is a bottom plan view thereof;
FIG. 20 is another front side perspective view of the watch assembly showing portions thereof in the second alternate position;
FIG. 21 is a front elevational view thereof;
FIG. 22 is a right elevational side view thereof, the side opposite being a mirror image;
FIG. 23 is a rear elevational view thereof;
FIG. 24 is a top plan view thereof; and
FIG. 25 is a bottom plan view thereof.
